UNITED STATES PATENT OFFICE.

EDWARD SEYMOUR AMROCK, OF WALTHAM, MASSACHUSETTS.

SHAVING-BRUSH.

1,182,235.

Specification of Letters Patent.

Patented May 9, 1916.

Application filed May 10, 1915. Serial No. 27,168.

To all whom it may concern:

Be it known that I, EDWARD SEYMOUR AMROCK, a citizen of the United States, residing at Waltham, in the county of Middlesex and State of Massachusetts, have invented a new and useful Shaving-Brush, of which the following is a specification.

The device forming the subject matter of this application is a shaving brush, and one object of the invention is to provide a device of this type which embodies a soap holder.

A further object of the invention is to provide novel means for guiding the respective parts with respect to each other, and for holding said parts in proper relative positions.

A further object of the invention is to provide novel means whereby a groove which constitutes a part of the guiding means may be shielded and protected when the structure is not in use and when the structure is in use.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing: Figure 1 shows the invention in side elevation, the same being in the condition which it will assume when not in use; Fig. 2 is a composite side elevation showing the structure as it will appear when its constituent parts have been separated partly; Fig. 3 is a side elevation showing the structure set up for use as a brush; Fig. 4 is a longitudinal section of the device when the parts are arranged as depicted in Fig. 1. Fig. 5 is a cross section on the line 5—5 of Fig. 2.

In carrying out the present invention there is provided a handle denoted generally by the numeral 1, the same comprising a tubular body 2 receiving a thimble 3 holding bristles 4 constituting a brush, it being understood that the bristles 4 may be assembled with the thimble 3 in any desired

manner. The thimble 3 is provided with a circumscribing groove 5 adapted to receive a circumscribing rib 6 on the body 2, to the end that the thimble may be held in place in the body. The tubular body 2 is open at its rear end, as shown at 50, so that the body may be employed for receiving and holding a cake of shaving soap indicated at 51.

Mounted to slide longitudinally of the body 2 of the handle and to rotate thereon is a tubular casing 7 carrying a projection 8 one end of which is adapted to ride in a groove 9 formed in the body 2 and to enter the extensions 10 and 11 of the groove, the extensions projecting transversely of the body 2.

The invention comprises a primary cap 12 adapted to fit over the end of the casing 7, the cap 12 being provided with a longitudinal slot 14 having a transverse extension 15. A secondary cap 16 fits over the body 2 and houses the groove 9, the secondary cap abutting against the casing 7 when the parts are arranged as shown in Fig. 1. The cap 16 is provided in its side with openings 17.

When the parts are arranged as shown in Fig. 1, the casing 7 is advanced until the same houses the brush 4, the casing being rotated until the inner end of the projection 8 is lodged in the extension 11 of the groove 9. The primary cap 12 is slipped over the end of the casing 7 and houses the brush 4. The secondary cap 16 is placed on the end of the body 2 and abuts against the casing 7, the secondary cap housing the groove 9.

When it is desired to use the structure as a shaving brush, the casing 7 is retracted until the brush 4 is uncovered, the casing being rotated until the inner end of the projection 8 lodges in the extension 10 of the groove 9, the secondary cap 16 being removed. When the primary cap 12 is placed on the end of the casing 7, the outer end of the projection 8 enters the slot 14 and ultimately lodges in the extension 15 of the slot 14 when the cap 12 is rotated.

The body 2 is adapted to contain the cake of soap 51 when the device is in use and when it is not in use, although if desired, the cake of soap 51 may be removed from the body 2 and be placed in the cap 16, it being possible under such circumstances to insert a finger into the opening 17 for the purpose of advancing the soap.

Having thus described the invention, what is claimed is:—

1. In a device of the class described, a handle; a brush carried by the handle; a casing slidable upon the handle and constituting a protection for the brush; a secondary cap mounted on the butt of the handle and engaged terminally with the casing; and a primary cap on the brush shielding end of the casing, the primary cap being adapted for mounting on the butt end of the casing when the casing is retracted and when the secondary cap is removed.
2. In a device of the class described, a handle having a longitudinal groove provided at its ends with transverse extensions; a brush carried by the handle; a casing slidable upon the handle and constituting a protection for the brush; a projection carried by the casing, one end of the projection being adapted to ride in the groove and to enter the extensions thereby to hold the casing in advanced and in retracted positions with respect to the brush; a secondary cap mounted on the butt end of the handle and engaged with the casing, the secondary cap constituting a protection for the groove; and a primary cap adapted for mounting on the brush shielding end of the casing when the casing is advanced, and adapted for mounting on the butt end of the casing when the casing is retracted and when the secondary cap is removed, the primary cap having

a slot receiving the other end of the projection when the casing is in retracted position. 35

3. In a device of the class described, a tubular body provided at its forward end with a brush and open at its rear end, the body having a bayonet slot; a sleeve surrounding the body and slidable thereon, the sleeve shielding the brush, the sleeve having a projection the inner end of which is received in the bayonet slot; the outer end of the projection extending beyond the sleeve; a primary cap on the forward end of the 40 sleeve and shielding the brush, the primary cap having a bayonet slot; a secondary cap on the rear end of the body, the secondary cap being removable, a covering for the bayonet slot in the body, a closure for the 45 compartment, and an abutment for the sleeve to prevent the rearward movement thereof; the primary cap being mountable on the rear end of the sleeve when the secondary cap is removed and when the 50 sleeve is retracted; the bayonet slot of the primary cap being adapted to receive the outer end of the projection on the sleeve.

In testimony that I claim the foregoing as my own, I have hereto affixed my signature in the presence of two witnesses: 55

EDWARD SEYMOUR AMROCK.
